(57) **CLAIM**

The ornamental design for a "self-filling pet water bowl," as shown and described.

DESCRIPTION

FIG. 1 is a perspective view of a self-filling pet water bowl showing my new design;
FIG. 2 is front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof, and,
FIG. 8 is front elevation view thereof, partially cut-away to reveal details of the top.
The portions in broken line are not claimed.
